(57) **CLAIM**

(21) Appl. No.: **29/607,506**

The ornamental design for an in-line thermometer, as shown and described.

(22) Filed: **Jun. 14, 2017**

DESCRIPTION

(51) **LOC (11) Cl.** **10-04**

FIG. 1 is a perspective view of an in-line thermometer according to the present application;

(52) **U.S. Cl.**

FIG. 2 is another perspective view of the in-line thermometer according to the present application;

USPC **D10/57**

FIG. 3 is a top view of the in-line thermometer according to the present application;

(58) **Field of Classification Search**

FIG. 4 is a bottom view of the in-line thermometer according to the present application;

USPC D10/57

FIG. 5 is a front view of the in-line thermometer according to the present application;

CPC G01K 1/14; G01K 13/00; G01K 13/02;

FIG. 6 is a rear view of the in-line thermometer according to the present application;

G01K 13/022; G01K 2013/024; G01K

2013/026; G01K 13/028

FIG. 7 is a left view of the in-line thermometer according to the present application; and,

See application file for complete search history.

FIG. 8 is a right view of the in-line thermometer according to the present application.

(56) **References Cited**

The hex nut, shown at the top left of FIG. 1 and in various other figures, is free rotating. The rotational position of the hex nut is not claimed.
